UNITED STATES PATENT OFFICE.

JACK L. BUCHANAN, OF LAWTON, OKLAHOMA.

DESIGN FOR A PIN OR SIMILAR ARTICLE OF JEWELRY.

Application filed October 8, 1923. Serial No. 7,425. Term of patent 7 years.

To all whom it may concern:

Be it known that I, JACK L. BUCHANAN, a citizen of the United States, residing at Lawton, in the county of Comanche and State of Oklahoma, have invented a new, original, and ornamental Design for a Pin or Similar Article of Jewelry, of which the following is a specification, reference being had to the accompanying drawing, forming part thereof.

The figure is a perspective view of a pin embodying my design.

I claim:

The ornamental design for a pin or similar article of jewelry, as shown.

JACK L. BUCHANAN.
